UNITED STATES PATENT OFFICE.

POWERS A. WICKES, OF PORTLAND, OREGON.

SAFETY BUTT-HOOK.

1,232,417.

Specification of Letters Patent. Patented July 3, 1917.

Application filed August 2, 1915. Serial No. 43,325.

To all whom it may concern:

Be it known that I, POWERS A. WICKES, a citizen of the United States, and a resident of Portland, county of Multnomah, 5 and State of Oregon, have invented a new and useful Improvement in Safety Butt-Hooks, of which the following is a specification.

My invention relates to hooks, such as 10 butt-hooks, which are used for carrying a rope or cable. Frequently, when a hook of this character is being used for lifting or hauling objects, the rope or cable will accidentally slip off the hook.

15 The object of my invention is to provide a hook with simple means for preventing the displacement of the line, or other object from the hook while the latter is doing work.

20 I attain the object of my invention by combining with my butt-hook a latch element adapted to be interlocked with, and released from, the bill of the hook by the simple act of positioning the shackle in its line of draft and rotating the same through 25 an arc of 90 degrees.

The construction and operation of my 30 improved hook will be more readily understood from a detailed description of the accompanying drawings constituting a part hereof.

In such drawings,

Figure 1 is a front elevation of a butt-hook embodying my invention.

35 Fig. 2 is a side elevation thereof, and Fig. 3 shows a vertical sectional elevation of my improved hook with the shackle rotated 90 degrees, for the purpose of disengaging the latch bar from the bill of the 40 hook.

The shackle *a* is preferably made bifurcated. The extremities *a'* having holes drilled therein, in which is inserted the shackle hinge pin *b*. The shackle or hinge 45 pin *b* is made non-rotatable relative to the shackle. This may be effected by any convenient means; as shown, the holes in the shackle ends *a'*,—and the pin *b* are made with flat portions as indicated at *b'*, in Fig.

50 3, for the purpose stated. The extremities of the shackle or the shackle hinge-pin *b* are formed with trunnions *c* located on an axis eccentric to the axis of rotation of the shackle. In the construction shown, the

trunnions are formed by drilling an eccentric longitudinal hole in the shackle-pin, and driving a pin *c'* therethrough. Between the extremities *a'* of the shackle *a*, there is hinged on the hinge pin *b*, a hook *d*, provided at its bill with the latch notch or 60 recess *e*. On the trunnions *c* are hinged the arms *f'*, of the bifurcate latch *f*, and the latter is provided with a cross-bar or portion *g*, adapted to engage in said latch notch *e*.

From the description given it is evident that the rotation of the shackle *a*, through an arc of 90 degrees will move the trunnions *c* from the position shown in Fig. 2, to the position shown in Fig. 3, in so 70 doing moving the cross-bar *g* of the latch *f* out of engagement from the notch or recess *e* of the bill of the hook *d*. The latch *f* may then be swung free of the hook and the rope or cable carried by the latter may 75 be removed. When the hook is to be used in work such as suspending or holding an object, the latch *f* is first moved into its position in Fig. 3. The load may then be affixed on the hook, the latch arranged so 80 that its cross bar *g* will rest against the bill of the hook, and by then moving the shackle into its load-pulling position, as shown in Figs. 1 and 2, and also indicated in Fig. 3 by broken outline, said cross bar of the 85 latch *f* will be drawn into the recess *e* of the bill of the hook, and in so doing lock the latch *f* in place and prevent the accidental dislodging of the load, preventing any accidental displacement of the rope or cable 90 carried by the hook.

I claim:

1. In a butt-hook, the combination of a clevis, a hinge pin carried non-rotatably by the extremities of the clevis, a hook hinged 95 on said pin, trunnions projecting from the extremities of said hinge pin and located eccentric to the axis of the latter, a latch hinged on said trunnions, means on the bill of the hook for engaging the middle part of the latch, whereby, when said clevis is positioned in the line of draft, the middle portion of the latch will be locked with the bill of the hook, and when said clevis is rotated out of its line of draft said latch will be 100 released.

2. In a butt-hook, the combination of a clevis, a hinge pin carried non-rotatably by

the extremities of the clevis, a hook hinged on said pin, trunnions projecting from the extremities of said hinge pin and located eccentric to the axis of the latter, a latch 5 hinged on said trunnions, the bill of the hook being provided with a recess adapted to receive the middle part of said latch,

whereby, when said clevis is positioned in the line of draft, the middle portion of the latch will be locked with the bill of the hook, and when said clevis is rotated out of its line of draft said latch will be released.

POWERS A. WICKES.
